UNITED STATES PATENT OFFICE.

JUSTUS J. HENDRICKSON, OF NORRISTOWN, ASSIGNOR OF ONE-HALF TO
CHARLES K. BULLOCK, OF PHILADELPHIA, PENNSYLVANIA.

CENTRIFUGAL SEPARATOR.

SPECIFICATION forming part of Letters Patent No. 297,994, dated May 6, 1884.

Application filed January 8, 1884. (No model.)

To all whom it may concern:

Be it known that I, JUSTUS J. HENDRICKSON, of Norristown, county of Montgomery, and State of Pennsylvania, have invented an improvement in Centrifugal Separators, of which the following is a specification.

My invention has reference to centrifugal separators for milling purposes; and it consists in certain improvements set forth in the following specification and shown in the accompanying drawings, which form part thereof.

The object of this invention is to provide a machine which shall be capable of separating the partially-reduced grain from the flour in an efficient manner.

In the drawings, Figure 1 is a longitudinal sectional elevation of a centrifugal separator embodying my improvements on line $x\ x$ of Fig. 2. Fig. 2 is a cross-section of same on line $y\ y$ of Fig. 1. Fig. 3 is a cross-section of same on line $z\ z$ of Fig. 1. Fig. 4 is an elevation of the feeding end of the machine. Fig. 5 is an elevation of the delivery end of the machine. Fig. 6 is an elevation of the adjustable bearings for the reel and beater shafts. Fig. 7 is an enlarged cross-section of a part of the reel and beater. Fig. 8 is a perspective view of the screen-frame removed from the reel, and Fig. 9 is an enlarged view of a portion of the feeding-head of the reel to show the packing.

A is the hopper, into which the flour to be treated is discharged. From this hopper it passes down into the chamber B, and is received upon an endless band, C, carrying brushes C', and running over two rollers, C'', one at each end of the said chamber.

c is a board, which is located immediately below the band C as it passes under the hopper. The flour is thereby carried over one of the rollers C'', and deposited on the screen B', over which it is swept by the brushes, the finer particles passing through into the feed-chamber D, and the larger particles and impurities being brushed over the incline B'', and discharged by tube B' from the machine or into the return-conveyer. The flour which passes into the chamber D is in good condition for the centrifugal action of the machine. As the

screen B' extends across the machine, there is a constant shower of flour descending, thereby tending to keep it in a less packed condition than has heretofore been the case. The falling flour is received upon the curved floor d, at the bottom of the chamber D, from which it is picked up and discharged into the reel by scoops e', having their openings pointing in the direction of rotation of the reel, and carried upon the reel-head E' of the reel, and arranged to form a curved or oblique passage-way through said reel-head by meeting with the apertures or perforations e. This head E' is secured to a sleeve, E'', which encircles the beater-shaft F, whereby the reel is adapted to rotate upon said shaft F, and rotates within a perforated partition, D', which it loosely fits, being made sufficiently air-tight by a packing, d', secured to said partition. The scoops thus feed the finely-divided material falling through the screen directly into the reel without compressing and caking it, as is the case with the screw-feed.

The discharging-head H of the reel is made identically like the feeding-head just described, and as it is designed to free the tailings from the reel into the chamber I, from which they pass by spout I', the scoops h', fitting over the apertures h, are upon the inside of the reel, as shown. This head H rotates in a perforated partition, I', and the joint is packed at i, as before, and this head is secured upon a sleeve, H'', carried by the beater-shaft as before.

If desired, the discharge spouts or scoops may be arranged upon the outside of the reel-head, and so formed as to offer a retarding effect to the tailings. I however prefer a positive feed and positive discharge to prevent overloading the reel, and thus render it capable of performing its function to the best advantage.

The two heads E' and H are secured together by longitudinal ribs or bars E, having projecting edges e'', and between which the screen-frames E'', carrying the screens e'', are placed and secured as shown in Figs. 2 and 7. This construction enables the screens,

when injured or worn out, to be readily removed and replaced, and at the same time presents a practically smooth or unobstructed surface on the interior.

- 5 The beater-shaft F carries secured to it a number of spiders, F', to the small arms of which are secured the beaters f, having the oblique parts f' on their front faces, so as to tend to throw the flour toward the screens of the reel.
- 10 This shaft F and sleeves E² H² are supported and work in adjustable bearings G, (shown in Fig. 6,) by which the heads E H may be adjusted perfectly in the apertures in the partitions D' and I', and prevent binding, either
- 15 when first setting the machine in operation or after the frame has warped, and is an improvement of much importance.

Secured to one end of the shaft F is the drive-pulley N, and secured to the other end is the sprocket-wheel H', which drives another sprocket-wheel, N³, secured upon a shaft, N², by a chain, n. This shaft N² is carried in adjustable bearing N', and has secured to it on the other end a pair of sprocket-wheels, N⁴ N⁵, one of which drives the pulley C² of the auxiliary feed by a sprocket-wheel, C¹, and chain C⁴, and the other the reel and conveyers K K by sprocket-wheels M M² M² and chain M', as shown in Fig. 4. The adjustable bearings N' of shaft N² enable the chains n M' and C⁴ to be tightened.

The conveyers K K are arranged in the same plane side by side, and in compartments J² J², separated by a board, L', both of which compartments open into the reel-chamber above, as shown in Fig. 2, and the entrance to said compartments J² from said reel-chamber is divided into a series of passages by vertical division-boards J', between which are valves L, pivoted at their lower ends above said board L', and provided near their upper ends with eyes l, by which to move them. By moving these valves to one side or the other the good flour may be conveyed to one conveyer and the other to the return-conveyer.

J³ are doors which open into said passage-way to expose the valves when desired either for inspection or for operation. There is also a compartment, d', below the feed-chamber D, the bottom of which is also provided with a valve. This chamber is called the "speck-box," and is designed to receive any flour which might escape through cracks or any aperture from the feed-compartment, and turn it into the return-conveyer.

While I prefer the construction shown, I do not limit myself to the details, as they may be modified in various ways without departing from my invention.

60 Having now described my invention, what I claim as new, and desire to secure by Letters Patent, is—

1. In a centrifugal separator, the combination of the reel having a solid head on its feeding end, said head being provided with apertures or slots, and hoods for said apertures, with

a feed-box in which said hoods rotate to scoop up the flour, and means to feed the flour into said feed-box in a continuous shower the full width of the end of the reel, substantially as 70 and for the purpose specified.

2. In a centrifugal separator, the combination of the reel having a solid head on its feeding end, said head being provided with apertures or slots, and hoods for said apertures, with 75 a feed-box in which said hoods rotate to scoop up the flour, a screen covering the top of said feed-box, and a brush adapted to pass over said screen to feed the flour through said screen into said feed-box, substantially as and for the 80 purpose specified.

3. In a centrifugal separator, the combination of the reel having a solid head on its feeding end, said head being provided with apertures or slots, and hoods for said apertures, with 85 a feed-box in which said hoods rotate to scoop up the flour, a screen covering the top of said feed-box, and a brush adapted to pass over said screen to feed the flour through said screen into said feed-box, and a discharge from one 90 end of said screen, through which any lumps or impurities are discharged to prevent clogging of said screen, substantially as and for the purpose specified.

4. In a centrifugal separator, the combination of the reel having a solid head on its feeding end, said head being provided with apertures or slots, and hoods for said apertures, with 95 a feed-box in which said hoods rotate to scoop up the flour, a screen covering the top of said feed-box, and a brush adapted to pass over said screen to feed the flour through said screen into said feed-box, a return-conveyer, and a discharge from one end of said screen, and connecting with the return-conveyer, through 100 which any lumps or impurities are discharged to prevent clogging of said screen, substantially as and for the purpose specified. 105

5. In a centrifugal separator, the combination of the reel having a solid head on each end, 110 said heads being provided with apertures or slots, and hoods for said apertures, to insure a positive feed and a positive discharge and prevent the overloading of the reel, with a feed-box in which said hoods rotate to scoop up the 115 flour, a long flat screen covering the top of said feed-box, and a flat brush adapted to pass over said screen from one end to the other, to feed the flour through said screen in a continuous shower into said feed-box, substantially 120 as and for the purpose specified.

6. A reel having a closed head, in combination with a stationary perforated partition or ring-piece, in which said solid head works, the reel-shaft, and adjustable bearings, whereby said reel may be set true with respect to said stationary partition or ring and prevent wear and binding should the frame become warped or shaft-worn, substantially as and for the purpose specified. 125

7. The combination of the reel with an auxiliary feeding device, which consists of a long 130

flat stationary screen, upon which the flour is brushed, a flat traveling brush moving over said screen, and means to feed the flour upon said screen, whereby the flour is caused to fall in a continuous shower, substantially as and for the purpose specified.

8. In a centrifugal separator, a reel-head provided with a positive feeding device, in combination with an auxiliary screening device consisting of a long flat stationary screen, upon which the flour is brushed, a flat traveling brush moving over said screen, and means to feed the flour upon said screen, whereby the flour is caused to fall in a continuous shower to first make a separation of the flour or middlings from lump impurities, &c., and then deliver said flour or middlings to said positive feeding device, substantially as and for the purpose specified.

20 9. The auxiliary feed, consisting of chamber B, having hopper A and board B², in combination with band C, brushes C', screen B',

pulleys C², and discharge B³, substantially as and for the purpose specified.

10. The auxiliary feed, consisting of chamber B, having hopper A and board B², in combination with band C, brushes C', screen B', pulleys C², inclined board c, and discharge B, substantially as and for the purpose specified.

11. In a centrifugal separator, the combination of a reel, a beater, beater-shaft F, sprocket-wheel H', chain n, shaft N, supported in adjustable bearings N', sprocket-wheels N⁴, conveyer sprocket-wheels M², sprocket-wheel M, sleeve E², and chain M', whereby said shaft N² and its wheels may be adjusted to tighten all of the working-chains, substantially as and for the purpose specified.

In testimony of which invention I hereunto set my hand.

JUSTUS J. HENDRICKSON.
